CLAIM

What is claimed is the ornamental design for a bracket for holding a user receiving device, as shown and described.

DESCRIPTION

This Application is related to U.S. application Ser. Nos. 14/447,150, 29/497,996 and 29/497,998 filed concurrently herewith, the disclosures of which are incorporated herein by reference.

FIG. 1 is a perspective view of a bracket for holding a user receiving device;

FIG. 2 is a top elevational view thereof;

FIG. 3 is a front elevational view thereof;

FIG. 4 is a bottom side elevational view thereof;

FIG. 5 is a back side elevational view thereof;

FIG. 6 is a right elevational view thereof; and,

FIG. 7 is a left elevational view thereof.

The broken line depicts environmental subject matter that forms no part of the invention.
